Inventor
Paul Young
By his Attorney

P. J. Garboe

UNITED STATES PATENT OFFICE.

PAUL YOUNG, OF PORT ARTHUR, TEXAS, ASSIGNOR TO THE TEXAS COMPANY, OF NEW YORK, N. Y., A CORPORATION OF TEXAS.

STILL.

Application filed June 5, 1920. Serial No. 386,878.

To all whom it may concern:

Be it known that I, PAUL YOUNG, a citizen of the United States of America, and a resident of Port Arthur, county of Jefferson, and State of Texas, have invented certain new and useful Improvements in Stills, of which the following is a specification, reference being had to the accompanying drawings, forming a part thereof.

My invention relates to stills and has special reference to coke stills in which petroleum oil is reduced to coke.

Coke stills such as are used in oil refineries for reducing oils such as crude petroleum to coke, are very large, being frequently 40 feet in length and 14 feet in diameter. Intense heat is applied to the still but as long as any liquid oil remains in the still, the strains due to the expansion, are not excessive. However, when the lighter products are vaporized and driven off, leaving the dry coke on the bottom of the still, the temperature of the bottom plates is greatly increased and expansion in the usual still structures, frequently shears the rivets on the bottom seams and necessitates the early replacement of the entire bottom of the still.

It has been my aim to overcome this difficulty, and according to my invention, I space apart the heavy bottom plates of the still and interpose comparatively light or soft expansion strips or plates. These plates or strips may buckle to a greater or less degree when the expansion occurs, but the rivets will not be sheared off and when the strips give out it is only necessary to replace them instead of replacing the entire bottom of the still.

In order that my invention may be thoroughly understood, I will now describe the same in the following specification and will then point out the novel features thereof in appended claims.

Referring to the drawings:

Figure 1 is a side elevation of a still arranged and constructed in accordance with my invention and constituting one embodiment thereof.

Figure 2 is a sectional elevation, taken on the line 2—2 of Figure 1.

Figure 3 is a detail view drawn to a larger scale, showing the joint between a heavy still bottom plate, a lighter lug sheet

or side plate, and an expansion sheet or strip 55 which is relatively thin.

10 designates a coke still of usual form, having top sheets 11, side or lug sheets 12, and relatively heavy and rigid still bottom sheets 13. In accordance with my invention 60 the still bottom sheets 13 are spaced apart longitudinally of the still as shown in Figure 1, and relatively thin expansion sheets 14 are interposed. The heavy bottom sheets 13 in the arrangement shown, overlap the lug 65 sheets 12 while the expansion sheets are inside and overlap both the lug sheets and the heavy bottom sheets. The sheets are riveted, welded, or secured together in any suitable manner.

The expansion plate is characterized by the fact that it is adapted to yield before the adjacent bottom plates and consequently will avoid shearing off the rivets or breaking the joints between the plates. As illustrated, 75 the expansion plates 14 are thinner than either the lug sheets or the bottom sheets, but this is not essential and similar results may be secured by making the expansion sheets softer or of metal having a lower 80 melting point than the still bottom sheets or, if desired, thinner expansion plates of softer material, or having a lower melting point, than the base plates, may be employed.

My invention and its advantages will be 85 readily understood by those skilled in this art, and I intend no further limitations other than those imposed by the appended claims.

What I claim is:

1. A coke still having a still bottom formed of spaced still bottom plates, and interposed relatively yieldable flat expansion sheets.
2. A coke still having a still bottom formed of spaced still bottom plates, and interposed relatively thin expansion sheets.
3. A coke still having a still bottom formed of spaced still bottom plates of relatively hard metal, and interposed expansion sheets of softer metal.
4. A coke still having a still bottom formed of spaced still bottom plates made of metal having a relatively high melting point and interposed expansion sheets made of metal having a lower melting point.
5. A coke still having a still bottom formed of spaced still bottom plates and

- interposed relatively thin non-corrugated expansion sheets.
6. A coke still having its bottom portion formed of alternately disposed relatively thick and thin plates secured together.
7. A still for reducing crude oil to coke of substantially cylindrical form having approximately 160 degrees of the lower portion of its periphery constructed of relatively heavy plates spaced apart longitudinally of the still and interposed relatively thin expansion sheets.
8. A coke still having a bottom formed of a plurality of spaced bottom plates of relatively rigid material, and an interposed relatively yieldable flat expansion sheet interposed between said rigid plates.

In witness whereof I have hereunto signed my name this 25 day of May 1920.

PAUL YOUNG.
